BIRDHOUSE

Raymond E. McGreevy, River Forest, and Frank M. Vondrasek, Downers Grove, Ill.; said Vondrasek as signor to said McGreevy

Filed June 21, 1960, Ser. No. 61,061

Term of patent 14 years

(Cl. D31—2)

Fig. 1.

Fig. 2.

Fig. 3.

Fig. 4.

FIGURE 1 is a front perspective view taken from right side of a birdhouse embodying our new design, the rear being substantially like the side shown;

FIGURE 2 is a top plan view thereof;

FIGURE 3 is a right side elevational view thereof, the left side not shown being substantially the same; and

FIGURE 4 is a bottom plan view thereof.

We claim:

The ornamental design for a birdhouse, as shown and described.
